UNITED STATES PATENT OFFICE.

ROBERT GEORGE McMAHON, OF ST. JOSEPH, ILLINOIS.

LOCK.

1,103,798.

Specification of Letters Patent. Patented July 14, 1914.

Application filed January 14, 1914. Serial No. 812,108.

To all whom it may concern:

Be it known that I, ROBERT G. McMAHON, a citizen of the United States, residing at St. Joseph, in the county of Champaign and State of Illinois, have invented new and useful Improvements in Locks, of which the following is a specification.

The invention relates to locks, and more particularly to the class of sliding door locks 10 for use on freight cars.

The primary object of the invention is the provision of a lock wherein the sliding door of a freight car will be firmly fastened in closed position so as to avoid the accidental 15 sliding thereof resultant from vibration imparted to the car during the travel of the same, thus obviating the possibility of the opening of the door, the lock being of novel form and is readily and easily operated.

Another object of the invention is the provision of a lock of this character wherein the parts thereof are concealed so as to render the lock burglar proof, strong, and durable.

A further object of the invention is the provision of a lock which is extremely simple in construction, reliable and efficient in its purpose, and inexpensive in manufacture.

With these and other objects in view, the invention consists in the construction, combination, and arrangement of parts as will be hereinafter fully described, illustrated in the accompanying drawing, and pointed out in the claim hereunto appended.

In the drawing: Figure 1 is a fragmentary 35 side elevation of a car body with its sliding door, showing the lock constructed in accordance with the invention applied. Fig. 2 is a view showing the lock in longitudinal sectional elevation. Fig. 3 is a sectional view on the line 3—3 of Fig. 1. Fig. 4 is a sectional view on the line 4—4 of Fig. 1.

Similar reference characters indicate corresponding parts throughout the several views in the drawing.

Referring to the drawing by numerals, A 45 designates a portion of the side wall of a car body having the usual doorway which is adapted to be closed by the sliding door B, on which is mounted the lock hereinafter 50 fully described.

The lock comprises a two part elongated 55 guide casing 5 in which is mounted a sliding latch bar 6 having a hook end 7 while its opposite end is pivoted at 8 to a link 9, the same being pivoted at 10 to a bell crank lever 11 which is swingingly supported upon a pivot

12 projecting from a base plate 13 secured to the door B, the lower longitudinal edge of the casing 5 being cut away to form a slot 13 through which moves the link 9 and the 60 handle portion 14 of the lever so as to avoid interference with the working of the lock.

Mounted on the side wall A of the car body at one side of the doorway is a keeper comprising a casing 15 in which is formed a 65 guideway 16 for the hook end 7 of the bar 6, and pivoted in this casing 15 above the path of movement of the bar is a locking pawl or dog 17 which is adapted to swing on the pivot 18 therefor to operate under 70 the tension of a leaf spring 19 suitably fixed within the casing 15 so that the pawl or dog 17 will trip over the hook end 7 for locking engagement therewith when the bolt is projected into the keeper casing 15 on 75 the closing of the door B, and thus lock the door in said closed position. The pivot 8 connecting the bar 6 and the link 9 together is extended into opposed slots 20 formed in the inner and outer sections of the casing 5 80 so as to guide the bar 6 to locked or unlocked position.

Mounted in the outer wall of the keeper casing 15 is a key receiving lock barrel 21 which is suitably connected with the pawl or dog 17 so that on the insertion of the key in the barrel 21 the latter can be turned for the lifting of the dog or pawl out of engagement with the hook end 7 of the latch bar 6 so that on moving the handle 14 in 90 one direction the latch bar 6 can be shifted for unlocking the door to free the same.

The meeting walls of the casings 5 and 15 are formed with alining loops 22 through which can be passed any ordinary well-known form of car seal so that should a malicious person be successful in releasing the lock it will be necessary to mutilate or break the car seal for the opening of the door, and thus indicate an unauthorized entrance to the car.

From the foregoing it is thought that the construction and manner of operation of the device will be clearly understood, and therefore a more extended explanation has 100 been omitted.

What is claimed is:—

A lock of the class described comprising a lock casing adapted to be secured to the casement of a door, a bolt casing adapted 110 to be secured to the door and having alining slots in opposite sides thereof, the said last-

named casing being provided with a slot at right angles to the first named slot, a sliding bolt in said bolt casing and movable into the lock casing, a bell crank shaped lever pivoted within the bolt casing and movable through the last-named slot, a link connecting the said lever with the said bolt, one of the connections of the link being slideable in the first-named slot in the bolt casing, a pawl pivotally mounted within the lock casing and engageable with the bolt to lock the

same, a spring acting upon the pawl to hold the same in the path of movement of the bolt, and key operated means within the lock casing for moving the pawl to released 15 position.

In testimony whereof I affix my signature in presence of two witnesses.

ROBERT GEORGE McMAHON.
